(57) **CLAIM**

The ornamental design for a vanity light fixture, as shown and described.

DESCRIPTION

FIG. 1 is a front, right, and top perspective view of a vanity light fixture, showing my new design;

FIG. 2 is a front, left, and bottom elevation view thereof; FIG. 3 is another front, right, and top perspective view of the vanity light fixture of FIG. 1 shown in an alternate configuration of use;

FIG. 4 is a front elevation view of FIG. 1;

FIG. 5 is a rear view of FIG. 1;

FIG. 6 is a left side elevation view of FIG. 1;

FIG. 7 is a right side elevation view of FIG. 1;

FIG. 8 is a top plan view of FIG. 1;

FIG. 9 is a bottom plan view of FIG. 1; and,

FIG. 10 is an enlarged view of an encircled area labeled "10" in FIG. 2.

The broken lines depict portions of the vanity light fixture in which the design is embodied that form no part of the claimed design. The additional dash-dot-dash lines in FIGS. 2 and 10 are for annotative purposes only and form no part thereof.
